UNITED STATES PATENT OFFICE.

LOUIS F. KULP, OF GWYNEDD, PENNSYLVANIA.

JAR-CAP FORMER.

1,418,939.

Specification of Letters Patent. Patented June 6, 1922.

Application filed September 5, 1919. Serial No. 321,781.

To all whom it may concern:

Be it known that Louis F. KULP, a citizen of the United States of America, residing at Gwynedd, in the county of Montgomery and 5 State of Pennsylvania, has invented new and useful Improvements in Jar-Cap Formers, of which the following is a specification.

The object of the invention is to provide a simple and inexpensive household device or 10 utensil adapted to re-form distorted jar and bottle caps such as those used in connection with preserving jars and the like, to refit them, with particular reference to their flanges, for efficient use when in the former 15 use thereof they have become distorted as by the bending or deflection of the flanges under such conditions as to prevent securing an air tight seal between the cap and the neck or shoulder of the jar.

20 It is a well recognized fact that the removal of a jar cap, particularly when accomplished by means of a mechanical device engaging the cap by a clamping action, the cap is more or less distorted from a 25 true cylindrical form, or the lip or flange with which such caps are ordinarily provided as a means of affording a bearing upon a rubber ring or gasket to secure an air-tight joint is bent or deflected, so that upon 30 subsequent use of the cap an ineffective joint is formed with the result that air is not excluded and deterioration of the contents of the jar results. It is with a view to re-forming or re-shaping such distorted caps, 35 to re-adapt them for use under as favorable conditions as originally, that the device forming the subject matter of this invention has been designed, and it will be understood that while a preferred embodiment thereof 40 is shown in the accompanying drawings, changes in the form and proportion thereof may be resorted to within the scope of the appended claims without departing from the principles involved.

45 In the drawing:

Figure 1 is a side view partly broken away of the former.

Figure 2 is a plan view of the same.

Figure 3 is a detail view of the operating 50 lever.

Figure 4 is a detail section showing a portion of a jar cap in operative relation with the members of the former.

Essentially the device consists of complementary forming members 10 and 11 of which the latter constitutes a base provided

with an annular mandrel 12 having an external contour corresponding substantially with the internal contour of the commercial jar cap or cover and including a shoulder 60 13 to support the flange or lip 14 of the cap or cover which is indicated at 15 in Figure 4. The member 10 of the apparatus is of annular form to fit down around the mandrel constituting the upper edge of the 65 base member and adapted to seat toward or upon the shoulder 13 so as to forcibly compress the interposed flange or lip 14 of the jar cap or cover and thus remove therefrom any waves or crimps which would tend to 70 prevent forming an efficient bearing of said flange or lip upon the packing gasket of the jar. The mandrel represented by the portion of the base member extending upward from the plane of the shoulder 13 is conical 75 or upwardly tapered so that when the jar cap or cover is fitted thereon and forced downwardly by the operation of the movable member of the former, it is returned to a truly circular form in the event that it has 80 been distorted by a lateral pressure or distorting strain incident to the use of a cap removing clamp or the equivalent thereof. The movable member of the former is preferably provided with a spider 16 from which 85 extends a stem 17 pivotally mounted as at 18 upon an operating lever 19 which in turn is fulcrumed at 20 upon the base member of the device, said movable member thus being adapted to have a sufficient latitude 90 of transverse movement to adapt itself to the jar cap or cover and apply pressure to the same in a direction substantially axial to the mandrel.

An extension 21 on the base member in the 95 plane of the operating lever serves to add to the stability of the device by resisting any tendency of the base member to tilt during the forcible operation of the lever.

What is claimed is:

1. A device for the purpose indicated consisting of complementary forming members of which one constitutes a base provided with an annular mandrel having an exterior contour corresponding substantially with the internal contour of a jar cap and including a shoulder to support the flange of such cap, the other of said members being provided with a spider having an up-standing stem, a lever fulcrumed upon the base member and pivotally connected to said stem and extended to provide a handle by means of which 105 110

the said other member may be forced into contact with the shoulder of the base member in the manner and for the purpose specified.

- 5 2. A cap reforming device consisting of complementary forming members of which one is adapted to form a base, the other of said members cooperating with the first to reform a distorted jar cap, a lever fulcrumed 10 on the base member and pivotally connected

to said upper member and extended to provide a handle, and an extension on the base member diametrically opposite the fulcrum point of said lever to resist any tendency of the base member to tilt during forcible operation of the lever. 15

In testimony whereof he affixes his signature.

LOUIS F. KULP.
